(57) CLAIM

The ornamental design for a toothbrush cover and holding assembly, as shown and described.

DESCRIPTION

FIG. 1 is a top, front, and right side perspective view of a toothbrush cover and holding assembly showing my new design, the broken-line disclosure of a pair of toothbrushes being for illustrative purposes only and forming no part of the claimed design;

FIG. 2 is a front elevational view of the holding assembly portion thereof, the rear being identical in appearance; FIG. 3 is a left side elevational view of the holding assembly portion thereof, the right side being identical in appearance; FIG. 4 is a top plan view of the holding assembly portion thereof;

FIG. 5 is a bottom plan view of the holding assembly portion thereof;

FIG. 6 is an enlarged left side elevational view of the cover portion thereof, the right side being a mirror image of that shown;

FIG. 7 is an enlarged front elevational view of the cover portion thereof;

FIG. 8 is an enlarged top plan view of the cover portion thereof; and,

FIG. 9 is an enlarged bottom plan view of the cover portion thereof.
